UNITED STATES PATENT OFFICE

JOHN EMIG, OF LANCASTER, PENNSYLVANIA, ASSIGNOR TO ARMSTRONG CORK COMPANY, OF LANCASTER, PENNSYLVANIA, A CORPORATION OF PENNSYLVANIA

FLEXIBLE HARD SURFACED FLOOR COVERING

Application filed May 7, 1929. Serial No. 361,076.

This invention relates to the manufacture of flexible hard surfaced floor coverings such as linoleum and a method and apparatus for the production thereof. It has heretofore been proposed to make surface coverings such as linoleum by applying overlying pattern elements to a base material. This is frequently done in a machine of the rotary type wherein the pattern elements are automatically cut out and applied by the die rolls of the machine. I provide a covering wherein there is a repeating pattern having overlying design elements. Instead of applying design elements to a plain backing which is partially or entirely covered, I first place design elements on the backing so as to form a pattern and then apply still further design elements which overlie those on the backing. In this way many new and desirable effects may be obtained. The material has characteristics not found in surface coverings of the types now made.

My method may be readily carried out in a machine of the rotary type. It is, however, necessary to modify the machine to the extent of positioning the die roll which applies the overlying design elements so that it is spaced in more than the ordinary amount from the backing. This is necessary in order that it will apply the design elements with the proper degree of pressure to the pattern elements previously applied.

In the accompanying drawings illustrating the present preferred embodiment of the invention,

Figure 1 is a diagrammatic view of a rotary machine,

Figure 2 is a view to an enlarged scale showing a portion of a drum of the machine and two of the die rolls thereof,

Figure 3 is a top plan view of one type of my improved product,

Figure 4 is a perspective view of a portion of such material, and

Figure 5 is a similar view showing another type of my improved material.

The machine shown in Figs. 1 and 2 comprises a drum 2 having die rolls 3 and 3a arranged around its periphery. Each die roll is supplied with a web 4 of linoleum mix-

formed by cylinders 5 and carried to the die rolls by belts 6. A platen roll 7 cooperates with each die roll and the surfaces of the die rolls are provided with knives in the usual manner to cut the webs of linoleum mix into pattern elements and scrap. The scrap is ejected by pin rolls 8 and brushes 8a as is well known, the scrap being carried away by conveyors 9.

A web 10 of backing material such as coated burlap is supplied to the machine and is carried around the drum 2. Each die roll is provided with a pattern roll 11 adapted to actuate the strippers 12 which have not been previously actuated by the pin rolls 8 and thus apply the pattern elements P forming the general body of the pattern to the backing 10. As shown in Fig. 2, the pattern elements P are spaced apart so as to expose a part of the coat backing 10, thus producing the effect of tiles with depressed interliners.

The overlying pattern elements are applied by the die roll 3a. As shown in Fig. 2, the die roll 3a is spaced further from the drum 2 than are the other die rolls, this being necessary because the design elements which are applied by the die roll 3a are not applied to the backing 10 but to the pattern elements P. The pattern elements which are applied by the die roll 3a are indicated at P' in Fig. 2.

After the various pattern elements have been applied, the material passes over an inspection table 13, and thence to a calender 14 having a blanket 15 backed by pressure rolls 16. The blanket securely bonds the different pattern elements to the backing and to one another, and if sufficient pressure is applied rounds off the edges as shown in Fig. 4. Care must be taken so as to avoid any distortion of the pattern elements P'. I prefer to make these pattern elements of relatively thin material so as to avoid distortion as far as possible.

Figures 3 and 4 illustrate a linoleum where in the pattern elements P are spaced apart so as to form a tile pattern with the backing showing between pattern elements. It will be noted that at intervals a specially colored pattern element P'' is applied. This lends variety to the appearance of the goods. Since

a single die roll can apply but one color, the special pattern elements P" are applied by hand as the material passes over the inspection table 13.

6 Figure 5 illustrates another type of material wherein the backing 10a is entirely concealed by pattern elements 17, which in this case are shown as made up into a conventional pattern of squares alternating in color. Special pattern elements 18 are applied. These may be put on by a die roll or may be applied by hand as desired. After calendering they are firmly keyed to the goods and provide a new and highly desirable effect.

10 15 I have illustrated and described a present preferred embodiment of the invention. It will be understood, however, that it is not limited to the form shown, but may be otherwise embodied or practiced within the scope 20 of the following claims:

I claim:

1. As a new article of manufacture, a flexible hard surfaced floor covering comprising a backing having pattern elements thereon, 25 there being design elements overlying the pattern elements.

2. As a new article of manufacture, a flexible hard surfaced floor covering comprising a backing having pattern elements of linoleum mix thereon and design elements of linoleum mix overlying at least some of the pattern elements.

3. As a new article of manufacture, a flexible hard surfaced floor covering comprising 35 a backing having pattern elements applied thereto in such manner as to leave portions of the backing exposed and design elements overlying at least some of the pattern elements.

40 4. As a new article of manufacture, a flexible hard surfaced floor covering comprising a backing having pattern elements applied thereto in such manner as to leave portions of the backing exposed and design elements 45 overlying at least some of the pattern elements, the design elements upstanding from the pattern elements and the pattern elements upstanding from the base.

In testimony whereof I have hereunto set 50 my hand.

JOHN EMIG.
